(57) **CLAIM**

The ornamental design for a front panel for an electronic housing, as shown and described.

DESCRIPTION

FIG. 1 is a front perspective view of a front panel for an electronic housing showing our new design;

FIG. 2 is a front view thereof;

FIG. 3 is a top view thereof;

FIG. 4 is a bottom view thereof;

FIG. 5 is a right end view thereof;

FIG. 6 is a left end view thereof; and,

FIG. 7 is a bottom view thereof.

The broken line bounded unshaded regions in FIGS. 1–6 form no part of the claimed design. The unshaded portions in FIGS. 1 and 5–7 form no part of the claimed design. The broken line regions in FIG. 7 are for illustrative purposes only and form no part of the claimed design.
